Application May 24, 1943, Serial No. 488,181

14 Claims. (Cl. 250—20)

1

This invention relates to radio receiving circuits and more particularly to radio circuits for translation of radio frequency pulses.

It is known that intelligence may be transmitted through wire or space by modulating a carrier wave in the form of a train of pulses wherein the intelligence is represented by variation in time such, for example, as variations in the time interval between pairs of pulses called "double pulse modulation." The duration of the pulses of the double pulse modulated wave are usually constant and small compared with the time intervals between adjacent pulses. In this kind of pulse modulation whether for transmission of voice, pictures, telegraph code, facsimiles or other intelligence, the pulses are preferably of equal amplitude and the modulation is determined solely by time displacement.

It is one of the objects of our invention to provide a circuit for translating such time modulated pulse carrier waves into equivalent trains of time modulated impulses of greatly amplified intensity.

Another object of our invention is to provide a radio receiver for time modulated pulse reception which is relatively simple and which requires only a small number of parts.

Still another object of our invention is to provide a single translation stage for translating time modulated pulse carrier waves into a train of time modulated impulses having an unusually large gain and a high signal-to noise ratio.

The principles of our invention are accomplished, for example, by a triggerable oscillating circuit having an output of impulses corresponding in occurrence to the pulse occurrence of a time modulated carrier wave or other time modulated pulse source applied thereto. The oscillating circuit is adjusted for normal interval operation at a frequency lower than the unmodulated frequency of a given carrier wave or other pulse source. The pulses of the source control the oscillation intervals of the circuit, and by providing a local pulse generator such as a multivibrator which is in turn controlled by the oscillation intervals of the oscillating circuit, rectangular impulses of constant predetermined duration having occurrence variations corresponding to the pulse occurrence of the carrier wave are produced. The rectangular impulses of the multivibrator may in turn be applied to the control circuit of the oscillating circuit to increase the sensitivity and stability thereof during the operating intervals thereof.

The output impulses thus produced may be ap-

2

plied to any desired form of T. M. (time modulation) demodulator such, for example, as disclosed in U. S. Patent to Reeves 2,266,401, or the copending application of D. D. Grieg Serial No. 459,959, filed September 28, 1942. The demodulation of the pulses translates the intelligence represented by the time variations thereof into corresponding amplitude variations which may be detected in the usual manner.

10 For a further understanding of the above and a further embodiment of the invention, reference may be had to the following detailed description to be read in connection with the accompanying drawings, in which:

15 Fig. 1 is a block diagram of one form of T. M. (time modulation) receiver in accordance with our invention;

Fig. 2 is a schematic wiring diagram of the oscillating trigger circuit of the embodiment 20 shown in Fig. 1;

Fig. 3 is a graphical illustration showing the translation operations of the circuit of Fig. 2;

Fig. 4 is a schematic wiring diagram of another embodiment of our invention showing a simplified 25 translating circuit; and

Fig. 5 is a graphical illustration showing the operating steps of the circuit in Fig. 4.

Referring to Fig. 1, the T. M. receiver therein shown for purposes of illustration includes the 30 usual antenna 10, an oscillating trigger circuit 12, a multivibrator circuit 14 and a T. M. (time modulation) demodulator 16. The oscillating circuit 12 controls operation of the multivibrator 14 and the multivibrator furnishes a feed-back volt-

35 age to the oscillating circuit. The normal operation of the oscillating circuit produces intervals or groups of oscillations and the occurrence of each group operates to trigger the multivibrator 14 from a first state of operation to a second state 40 of operation from which it is adapted to return to the first state after a predetermined interval. This operation of the multivibrator produces a voltage impulse of rectangular form which is fed back to the oscillating circuit to increase the

45 sensitivity and stability thereof during its operating intervals. The multivibrator pulses, correspond in occurrence with the pulse occurrence of the modulated carrier wave and their duration may be controlled independently of the operating 50 interval of the oscillating circuit. Either the multivibrator pulses or the average voltage pulse of the operating interval of the oscillating circuit may be applied to the demodulator 16 by selective operation of the switch 17 with respect to connec-

tions 19 and 37.

As shown in Fig. 2, an L-C resonant circuit is tuned to a particular carrier wave the R. F. energy of which is obtained from the antenna coupling coil 13. The oscillating circuit 12 is provided with a vacuum tube 20 having an anode 21, a control grid 22, a cathode 23 and a screen grid 24. One side 25 of the L-C circuit is connected through a blocking condenser 26 to the grid 22. The opposite side 27 of the L-C circuit is grounded. To complete the triggering circuit, the cathode 23 is connected to the coil L at 28. The screen grid 24 is connected to ground through a condenser 30 for by-passing the radio frequency energy. The screen grid is also connected to a movable contact of a potentiometer 32 which is supplied with positive energy from a battery terminal 34. The plate output circuit 35 is connected across a load resistance 36 to the battery terminal 34.

The multivibrator 14 is of known character having one state of operation from which it is capable of being triggered to a second state of operation from which it will return after a given interval of time to the first state of operation. The output of the multivibrator is preferably used as the time modulation output impulses since the duration thereof can be controlled independently of the operating interval of the oscillating circuit of tube 20.

By feeding back energy of the multivibrator pulse output over connection 37 to a voltage divider R_1 and R_2 to the grid 22, the sensitivity of the tube is greatly increased during the operating interval thereof. In other words, the multivibrator pulses insure continued oscillations of the circuit for the duration of the multivibrator pulses, thereby stabilizing the duration of the successive interval operations of the circuit. The resistor R_1 is preferably high to provide a high impedance to the R. F. energy of the grid circuit.

If desired the feed-back connection may be made to the screen grid 24 in place of grid 22.

In Fig. 3, curve *a* represents a period A of normal operation in absence of input signals and a period B during which input signals are received. Curve *b* represents generally the grid voltage of grid 22 during the periods represented by curve *a*. Curves *c*, *d* and *e* represent respectively, the voltage impulses produced by the multivibrator, the oscillation intervals of the oscillating circuit and envelope pulses produced from the oscillating energy.

Assuming that no input pulses are received (period A), the operation of the oscillating circuit 12 and the multivibrator 14 may be described as follows. When the potential on the grid 22 builds up to a critical value indicated by the level 40, curve *b*, oscillations will be initiated by thermal or random noise voltage fluctuations such as indicated at 41. The oscillations build-up rapidly as indicated by curve *d* and trigger the multivibrator 14 from one state of operation to a second state of operation thereby producing at the output thereof a pulse 42 (curve *c*) of rectangular shape. This pulse energy being applied to the grid 22 through the voltage divider R_1 , R_2 operates to increase substantially the grid voltage above the level 40 thereby increasing greatly the sensitivity of the tube. This insures maximum oscillations 44 as indicated by curve *d*. This oscillating energy is rectified in the plate circuit of the tube as indicated by the pulse envelopes 45 of curve *e*. The oscillating interval and therefore the envelopes 45 are terminated by the build-

ing-up of a negative charge on the condenser 26 to a value represented by the negative level 46.

A period free from oscillation follows the occurrence of each envelope during which the grid voltage becomes gradually less negative by leakage through resistors R_1 , R_2 until the grid voltage again reaches the critical level 40. In the absence of incoming pulses the initiation of oscillation is dependent upon random noise voltage fluctuations as indicated at 41 and therefore the normal period T_0 of the oscillation intervals may vary. When this frequency of operation is lower than the unmodulated pulse repetition frequency of the carrier wave (see period T_s), the signal pulses of the carrier wave will operate to initiate the oscillation intervals prior to the grid voltage reaching the critical level 40.

The pulse modulation of the carrier wave is represented in curve *a* by the signal pulses 51, 52 and 53, 54 wherein the signal pulses are in pairs as indicated and the maximum degree of modulation is represented by the difference in the intervals t_1 and t_2 . This double pulse modulation is chosen for purposes of illustration, it being understood that other forms of pulse modulation may be received where the translation is made into voltage impulses of a selected width according to adjustment of the multivibrator. As shown, the pulse 51 occurs prior to the grid voltage reaching the level 40 and the energy of the pulse when superimposed on the grid voltage (curve *b*) increases the grid voltage sharply above the level 40 thereby initiating the oscillation interval in coincidence with the leading edge of the pulse 51. The leading edges of the oscillations 51*d*, envelope 51*e* and the impulse 51*c* of the multivibrator, are all in substantial coincidence with the leading edge of the pulse 51.

Likewise, pulses 52, 53 and 54 synchronize the operation of the oscillating trigger circuit to produce the corresponding envelopes 52*e*, 53*e* and 54*e* and consequently the impulses 52*c*, 53*c* and 54*c*. It is readily apparent from an inspection of the graphical illustration of Fig. 3 that the leading edges of the impulses of curves *c* and *e* correspond in time displacement to the time displacement of the pulses of the modulated carrier wave of curve *a* and may be demodulated in the demodulator 16 in the manner disclosed in the aforesaid application Serial No. 459,959. The impulses of curve *c* are preferred for demodulation since their amplitudes are constant and the width of such pulses may be controlled independently of the oscillating intervals.

Referring to Figs. 4 and 5, the oscillating circuit-mutivibrator arrangement of Figs. 1 and 2 is replaced by a simplified oscillating circuit from which direct current impulses are obtained in response to the oscillation intervals of the oscillating circuit. The circuit of Fig. 4 comprises the usual antenna 60 which is applied to an inductance coil 62 through a coupling condenser 61 and an adjustable contact 63. The coil 62 is connected in parallel with an adjustable condenser 64 tunable to the R. F. frequency of pulse modulation carrier waves. A further tuning of the carrier wave detecting circuit 62, 64 is provided by a second adjustable condenser 65 which is connected between one side of the resonant circuit and ground. The side 67 of the resonant circuit is connected to the anode 68 of a vacuum tube 70. The side 69 of the resonant circuit is connected through a blocking condenser 72 to a control grid 73. The cathode 74 is connected to ground. An adjustable grid leak resistor 75

for the grid 73 is also connected to ground. The plate circuit of the tube is supplied with a positive potential from a battery terminal 76 through a resistor 77 and an R. F. isolating inductance coil 78 to the side 69 of the resonant circuit. Connected to this circuit between the resistor 77 and the coil 78 is an output connection 79 which is applied to the T. M. demodulator 80.

The operation of this circuit is similar to the circuit of Fig. 2 except that the oscillations applied across the plate and grid of the tube provides a flow of rectified current through the plate-grid circuit thereby building-up a negative voltage charge on the blocking condenser 72. The operating steps are illustrated by curves *g*, *h*, *i* and *j* of Fig. 5. Similarly as in the circuit of Fig. 2, each series of oscillations (curve *i*) produces a negative voltage (curve *h*) which build up on the condenser 72 until level 82 is reached thereby blocking the oscillations. The coil 78 blocks passage of the radio frequency component while permitting passage of the direct current component producing the voltage pulse across resistance 77. These pulses 85 are represented by curve *j*. The intelligence represented by their displacement by pairs (the extreme degree of displacement being represented by the intervals t_3 and t_4 between the successive pairs of pulses) may be demodulated in the usual manner by the demodulator 80.

From the foregoing description it is readily apparent that in accordance with our invention the negative value of the grid potential during the intervals between input signals is such as to maintain the circuit non-responsive to most noise voltage fluctuations thereby providing a high signal-to-noise ratio for the receiver. Further, the feed-back feature of the embodiments herein disclosed greatly increases desirably the gain of the triggering circuit.

While we have shown the principles of our invention in connection with specific apparatus, it is to be understood that the illustrations are given by way of example only and not as limiting the scope of the invention as set forth in the objects and the appended claims.

We claim:

1. A radio receiver for time modulated pulse reception, comprising an oscillating trigger circuit having normal interval operation at a lower frequency than the unmodulated pulse repetition frequency of a given time modulated pulse source, means controlled by the oscillations occurring in the oscillating circuit for each operating interval to produce a voltage impulse, means to apply energy received from said pulse source to said circuit to synchronously control the operation thereof, whereby the impulses produced correspond in occurrence to the pulse occurrence of said source, and means for demodulating the impulses.

2. The radio receiver defined in claim 1 wherein the means for producing said impulses includes a multivibrator having a mode of operation initiatable by the occurrence of oscillations in said oscillating circuit.

3. The radio receiver defined in claim 1 wherein the means for producing said impulses includes a condenser-resistor combination adapted to build-up a blocking voltage in response to oscillations in said circuit and to control the dissipation of the blocking voltage at a given rate selected in accordance with the unmodulated pulse repetition frequency of said pulse source.

4. The radio receiver defined in claim 1 where-

in the means for producing said impulses includes a multivibrator, means to apply the output of said oscillating trigger circuit to said multivibrator whereby the occurrence of oscillations causes the multivibrator to change from one state of operation to a second state of operation from which the multivibrator returns after a predetermined operation, and means to apply the impulse output of said multivibrator to the oscillating trigger circuit to increase the sensitivity thereof during the oscillating interval thereof.

5. The radio receiver defined in claim 1 wherein the oscillating trigger circuit includes a vacuum tube having plate, grid and cathode electrodes, said grid and cathode electrodes being connected

15 to the means for applying energy of said pulse source, means connected to the plate electrode for supplying the output impulses in response to oscillations established in the tube circuit, and means adjustable to control the bias of said tube.

20 6. A circuit for translating the pulses of a time modulated pulse source into an equivalent train of time modulated impulses comprising an oscillating trigger circuit having normal interval operation at a lower frequency than the unmodulated pulse repetition frequency of said pulse source, a multivibrator controlled by the occurrence of oscillations in said circuit for producing for each interval of operation an impulse of given duration, and means to apply energy of said given source to said circuit to synchronously trigger the operation thereof whereby the impulses produced by said multivibrator correspond in occurrence to the pulse occurrence of said source.

25 7. The circuit defined in claim 6, in combination with means to apply impulse energy from the multivibrator to the oscillating trigger circuit to increase the sensitivity thereof during oscillating intervals.

30 8. A circuit for translating the pulses of a time modulated pulse source into an equivalent train of time modulated impulses comprising an oscillating trigger circuit, means adjustable to establish the normal interval operation of said oscillating trigger circuit at a lower frequency than the pulse repetition frequency of said given source,

35 said circuit having a vacuum tube with plate, grid and cathode electrodes, an inductance-capacitance circuit tunable to receive energy of said given source, said inductance-capacitance circuit being connected across certain of the electrodes of said tube to provide a tube circuit in which initiation of oscillations is caused by the pulse energy of said source, and means controlled by the oscillations occurring in the tube circuit for producing an impulse, whereby the occurrence of pulses in said source operate to generate through the medium of said oscillating trigger circuit a train of impulses which correspond in occurrence to the pulse occurrence of said source.

40 9. The circuit defined in claim 8 wherein the means for producing the impulses includes a multivibrator having a mode of operation initiatable by the occurrence of oscillations in said tube circuit,

45 the plate electrode of said tube circuit being connected to the input of said multivibrator, and feed-back means connecting the output of said multivibrator to one of the electrodes of said tube.

50 10. The circuit defined in claim 8 wherein the tube includes a screen grid electrode and means to apply a source of voltage to said screen grid to control the normal operating frequency of the oscillating trigger circuit, and the means for producing the impulses includes a multivibrator hav-

ing a mode of operation initiatable by the occurrence of oscillations in said tube circuit and feedback means including a voltage divider connecting the output of the multivibrator to one of the electrodes of said tube.

11. The circuit defined in claim 8 wherein the means for producing the impulses includes a condenser-resistor combination coupled to the grid electrode of the tube, said condenser operating to build-up a negative charge during oscillations in said tube circuit, thereby providing a blocking voltage for the tube, and said resistor operating as a grid leak to control the discharge of the negative charge upon said condenser.

12. A circuit for translating a pulse modulated carrier into impulse envelope form comprising an oscillating trigger circuit having normal interval operation at a lower pulsing frequency than the unmodulated pulse repetition frequency of said carrier, means controlled by the oscillations occurring in the oscillating circuit to produce a voltage impulse of envelope form for each oscillating operating interval, and means to apply pulse modulated carrier energy to said circuit to synchronously control the operation thereof, whereby the impulses produced correspond in oc-

10 currence to the pulse modulation of said carrier.

13. The circuit defined in claim 12 wherein the means for producing said impulses includes a multivibrator having a mode of operation initiatable by the occurrence of oscillations in said oscillating circuit.

14. The circuit defined in claim 12 wherein the means for producing said impulses includes a condenser-resistor combination adapted to build-up a blocking voltage in response to oscillations in said circuit and to control the dissipation of the blocking voltage at a given rate selected in accordance with the pulse repetition frequency of said carrier wave.
